Belmont, Mass.

Application August 2, 1935, Serial No. 34,306

4 Claims. (Cl. 36—24.5)

This invention relates to the manufacture of shoes and contemplates a shoe wherein expensive materials are saved and weight reduced without detracting from the appearance or serviceability 5 of the shoe.

Our shoe is comparable in appearance and service to far more expensive shoes, but by reason of the manufacturing economies which we are able to effect can be produced at greatly reduced cost.

In carrying out our invention we use a special heel unit and a special outsole, and preferably connect the same by a bridge member in the form of a light-weight, inexpensive shank piece. 15 The heel unit and outsole are of such design as considerably to reduce the amount of expensive materials entering into the construction of the shoe, as well as considerably to reduce the weight of the shoe, and the light-weight inexpensive 20 shank piece strengthens or trusses the shoe in the regions of the outsole and heel unit where expensive materials have been removed.

These several features combine to produce in the completed shoe an unusually tight, snug and attractive joint between the upper materials of the shoe and the heel unit and between the heel unit and the outsole.

As illustrative of the principles of our invention we show in the accompanying drawing an embodiment thereof which we have found well adapted to the requirements of modern shoe manufacturing and highly satisfactory in actual service. In such drawing:

Fig. 1 is a fragmentary perspective of a shoe 35 of the McKay type in accordance with our invention, it being understood, however, that the principles of our invention are applicable to other types of shoes, as for example, the standard welt or welt sole type.

Fig. 2 is a partial longitudinal section.

Fig. 3 is an enlarged transverse section on the line 3—3, of Fig. 2, and

Fig. 4 is a perspective view of our novel heel unit, detached, and viewing the attaching face 45 thereof.

In carrying out our invention we use an outsole which has its heel area cut off along a line which when the outer sole is overlapped upon the heel brings the gradually beveled rear end of the outsole a substantial distance in rear of the heel breast, such an outsole being commonly termed a short sole.

With such an outsole we employ a heel unit of new structure and result. Our heel unit is a 55 whole or solid heel. It is also a cupped heel. At

its breast our heel unit is of greater height than the conventional rubber heel tap. Rearwardly from its breast our heel rapidly increases in height.

The attaching face of our heel unit comprises a cupped rear area which provides a concave heel seat. Forwardly of such concaved heel seat and in prolongation thereof the attaching face is inclined downwardly to form a depressed receiving recess adapted to snugly engage the beveled rear 10 end of the short outsole. Forwardly of such depressed sole-receiving recess and in prolongation thereof the attaching face is formed as a depressed shelf area adapted to snugly engage the under face of the short outsole. Both the depressed sole-receiving recess and the depressed shelf area extend across the width of the heel unit and are curved to correspond substantially to the transverse curvature of the concaved heel seat. The outer margin of the attaching face is 15 formed as an upwardly extending rim which bounds all of said areas and provides in the region of the cupped rear area a seating surface 20 adapted to snugly engage the upper materials of the shoe.

We have indicated at 10 a short outsole, having its rear or overlapping end gradually beveled rearwardly as at 11 for a distance substantially corresponding to the distance which the outsole 25 overlaps the heel unit.

In order further to reduce weight and save expensive materials, the upper face of the shank area of the outsole is hollowed out between its marginal edges as indicated at 12. The material of the outsole thus removed is substantially replaced and the outsole strengthened and stiffened by a shank piece 13 of lighter and more inexpensive material, such as wood, fibre, composition or the like. This shank piece substantially fills the hollowed out portion or concavity 12 and extends 35 rearwardly beyond the beveled rear end 11 of the outsole. The shank piece is slightly arched and at its forward end is secured to the usual innersole 26 of the shoe in any suitable manner as by gluing. If desired, the innersole 26 may be covered by any usual lining material 21.

With a shoe of the McKay type as shown in the drawing, the marginal edge of the outsole is preferably built up as at 14 as a stitch receiving edge of increased thickness. Where the outsole is of 50 molded rubber, such edge may take the form of alternate ridges and depressions simulating in general appearance the appearance of the mechanically formed wheel marks in a leather outsole.

With such a short outsole we use a unitary heel, meaning thereby a whole or solid heel which at its breast is of greater height than the conventional rubber heel tap and rearwardly from its breast gradually increases in height.

The rear area of the attaching face of said heel unit is cupped as at 15 to provide a concaved heel seat surface. Forwardly of the same and merging therewith is a substantial length of upwardly facing forwardly inclined area 16. In advance of and merging with said forwardly inclined area 16 is a depressed shelf area 17.

The forwardly inclined and shelf areas 16 and 17 are transversely curved to substantially correspond to the transverse curvature of the cupped rear area and the outer margin of the heel unit is extended upwardly as a rim 18. The marginal rim 18 bounds all of the areas 15, 16 and 17 and provides in the region of the cupped rear area a curved seating surface 19 adapted to snugly engage the upper materials S of the shoe, in the region of the forwardly inclined area 16 seating surfaces 20 adapted to snugly engage the beveled rear end 11 of the sole, and in the region of the shelf area 17 seating surfaces 21 adapted to snugly engage the underface of the outsole.

As a result of this construction, the heel when nailed as at N and N¹ affords a tight snug joint with the upper materials and with the outsole. The upper materials are snugly seated on the seating surface 19 formed by the upwardly extending marginal rim 18 adjacent the cupped rear area of the heel unit and the overlapping rear end of the short outsole is snugly seated upon the seating surfaces 20 and 21 formed by the rim 18 adjacent the depressed sole receiving recess formed by the areas 16 and 17.

Within the area of the heel unit bounded by the portions 15, 16 and 17 the attaching face of the heel unit is hollowed out as indicated at 22. This is done in the interest of reducing weight and saving expense of materials. The hollowed out portion 22, however, may be and preferably is of such design as to leave within the same one or more vertical ribs or supports 23 which strengthen and stiffen the heel in this region. As best shown in Fig. 4 these ribs 23 may be left in the form of a T with the cross bar of the T disposed toward the heel breast. Such arrangement is optional, however, and various other designs of stiffening and strengthening ribs may be employed.

With the form shown, the leg and cross bar of the T at their point of juncture afford a support and anchorage for the rear end of the shank piece 13 which thus bridges the outsole and heel unit and connects them as a structural tie member or truss.

Thus in our shoe weight is reduced and expensive materials saved. By using a short outsole we save substantially the weight and amount of material which in a full outsole would extend throughout the heel area of the shoe. By hollowing out such short outsole in its shank area we effect an additional saving in material and accomplish a still further reduction in weight due to the cheaper cost and lighter weight of the shank piece.

By using a unitary heel unit which is concaved so deeply within the marginal rim thereof that the upper materials of the shoe and the overlapping end of the short outsole fit within and make a tight and snug joint with said rim and by hollowing out such heel unit as at 22, we form in the attaching face of the heel unit

a hollow space which considerably reduces the amount of expensive material and greatly lightens the weight of the heel unit.

Thus referring to Fig. 3 we save the cost and weight of all the material of the heel unit in the space which is filled by the rear end of the shank piece as well as the cost and weight of the material of the heel unit lying on either side a of the shank piece and extending toward the lateral margins of the heel unit.

When the shoe is nailed, the outer row of nails N tend to draw the cupped margins of the heel unit upwardly against the upper materials as a tight snug joint in this region of the heel unit, certain of the nails N¹ in the shelf area 17 penetrate the shank piece which is thereby caused to press from above on the overlapping rear end of the outsole downwardly against the seating surfaces 20 and 21 of the heel unit.

The shank piece, moreover, fills the hollowed out portion 12 of the outer sole and lies substantially flush with the upper face of the outer sole without bulging or giving the effect of a thick shank. Instead, the effect is that of a rounded bottom in the region of the shank which is one of the characteristics of the more expensive shoes.

Thus in our shoe the shank piece replaces to some extent the heavier and more expensive material existing at the heel end of the full outsole, and in combination with the hollowed out recess 12 of the outsole and the concaved and hollowed out unitary heel unit provides a shoe which is actually lighter in weight and contains a lesser amount of expensive materials than the ordinary shoe with full outsole, heel lift or base, and conventional rubber heel tap. This not only accomplishes a saving in manufacturing costs but a saving in freight rates due to the reduction in weight of our shoe as compared with the more expensive shoes.

After a shoe constructed in accordance with our invention has been assembled, nailed and trimmed, the shoe is preferably finished in the heel area by staining the top portion of the heel unit as at 24 to simulate a heel base and by either leaving the lower portion of the heel unit unstained or if the heel unit was completely stained, then by scuffing off such lower portion as at 25 to give the effect of a half heel which simulates in height and appearance the height and appearance of the conventional rubber heel tap.

Where so treated, the stained upper portion 24 of our heel unit occupies the position normally occupied by the interposed heel base lift or lifts of leather in the more expensive shoe and is stained to simulate the same, and the lower portion 25 of our heel unit occupies the position and simulates in height and appearance the height and appearance of the conventional rubber heel tap. Thus, the shoe cannot be distinguished in appearance from the more expensive shoe.

Various modifications in procedure and materials may obviously be resorted to within the spirit and scope of our invention as defined by the appended claims.

What we therefore claim and desire to secure by Letters Patent is:—

1. A shoe comprising upper materials, a unitary heel and short outsole terminating within the bounds of the heel in a beveled end, the attaching face of said heel unit having a cupped rear area bounded by upwardly projecting margins adapted for contact with the upper ma- 75

- 5 terial of the shoe and being hollowed out within such margins and within such hollowed out portion having a seat for a shank piece, there being a substantial length of curved upwardly facing forwardly inclined area in prolongation of said cupped area and the margins of said inclined area extending upwardly to contact the overlapping end of said outsole and being in prolongation of the upwardly projecting margins of
- 10 said cupped area, a shank piece extending beyond the overlapping end of said outsole and seating on said seat included within the boundary of said hollowed out portion of the heel unit, and means uniting said outsole and heel
- 15 unit to the upper material of the shoe with the shank piece pressing the overlapping end of the outsole to its seat on said heel unit.
2. A shoe comprising upper materials, a unitary heel and short outsole terminating within the bounds of the heel in a beveled end, the upper face of said outsole in the shank area thereof being hollowed out, the attaching face of said heel unit having a cupped rear area bounded by upwardly projecting margins adapted for contact
- 25 with the upper material of the shoe and being hollowed out within such margins and within such hollowed out portion having a seat for a shank piece, there being a substantial length of curved upwardly facing forwardly inclined area in prolongation of said cupped area and the margins of said inclined area extending upwardly to contact the overlapping end of said outsole and being in prolongation of the upwardly projecting margins of said cupped area, a shank piece dis-
- 30 posed within the hollowed out portion of the outsole and extending beyond the overlapping end of said outsole and seating on said seat included within the boundary of said hollowed out portion of the heel unit, and means uniting said outsole and heel unit to the upper material of the shoe with the shank piece pressing the overlapping end of the outsole to its seat on said heel unit.
- 35 3. A shoe comprising upper materials, a unitary heel and short outsole terminating within the bounds of the heel in a beveled end, the upper
- 40 face of said outsole in the shank area thereof being hollowed out, the attaching face of said heel unit having a cupped rear area bounded by upwardly projecting margins adapted for contact with the upper material of the shoe and being hollowed out within such margins and within such hollowed out portion having a seat for a shank piece, there being a substantial length of curved upwardly facing forwardly inclined area in prolongation of said cupped area and the margins of said inclined area extending upwardly to contact the overlapping end of said outsole and being in prolongation of the upwardly projecting margins of said cupped area, a shank piece dis-
- 45 posed within the hollowed out portion of the outsole and extending beyond the overlapping end of said outsole and seating on said seat included within the boundary of said hollowed out portion of the heel unit, and means uniting said outsole and heel unit to the upper material of the shoe with the shank piece pressing the overlapping end of the outsole to its seat on said heel unit.
4. A shoe comprising upper materials, a short outsole having a hollowed out portion in its shank area, a unitary heel unit having a cupped rear area providing a concave heel seat bounded by upwardly projecting margins adapted for contact with the upper material of the shoe and having forwardly of said concave heel seat a depressed sole-receiving recess across the width of the heel and curved to correspond substantially to the transverse curvature of the concave heel seat, there being a hollowed out portion within the confines of said upwardly projecting margins, and a shank piece disposed in said hollowed out portion of the outsole and extending over said hollowed out portion of the heel unit as a bridge, and means uniting said outsole and heel unit to the upper material with the shank piece pressing the overlapping end of the outsole to its seat within said heel unit.
